UNITED STATES PATENT OFFICE.

HARVEY TILDEN, OF HARRISBURG, PENNSYLVANIA.

INTERLOCKING SWITCH AND SIGNAL APPARATUS.

SPECIFICATION forming part of Letters Patent No. 240,054, dated April 12, 1881.

Application filed June 28, 1880. (No model.)

To all whom it may concern:

Be it known that I, HARVEY TILDEN, of Harrisburg, county of Dauphin, State of Pennsylvania, have invented or discovered a new and useful Improvement in Interlocking Switch and Signal Apparatus; and I do hereby declare the following to be a full, clear, concise, and exact description thereof, reference being had to the accompanying drawings, making a part of this specification, in which—like letters indicating like parts—

Figure 1, Sheet 1, is a vertical sectional view of my improved apparatus as taken in the plane of the line xx , Fig. 6, looking to the left. Fig. 2 illustrates a modified construction of the devices for giving the motion which effects preliminary interlocking, as presently to be described. Fig. 3 is a sectional view lengthwise through the rotative shell of the handle and an elevation of the devices within, but to an enlarged scale. Fig. 4 is a vertical sectional view through the axial line of Fig. 3. Fig. 5 is a transverse section through the plane of the line $x'x'$ of Fig. 3. Fig. 6, Sheet 2, is an elevation of the machine from the left of Fig. 1, or from the operator's standpoint, certain parts in this figure, as in Fig. 1, being broken away, the better to show the devices beyond. Figs. 7, 8, and 9 are detached views, in perspective, of interlocking devices, but to an enlarged scale, the same to be presently explained.

My present invention relates to certain improvements in apparatus for actuating railway switches, signals, gates, &c., by hydraulic power, and for locking in any desired or predetermined position railway switches, signals, and gates, and also for interlocking the operative mechanism thereof, so that the shifting of one mechanism so as to bring a switch, signal, or gate into a desired position, shall operate to lock some other operative mechanism which is arranged to actuate some other switch, signal, or gate, whereby the shifting of the latter is prevented until such locking mechanism is reversed.

The conditions of use in apparatus of this kind and the general functions to be performed are so well known by those skilled in the art that they need not be here set forth at greater length.

It is also a part of my invention to effect what is known as "preliminary interlocking" by a construction and operation which I believe to be new. The frame A , of any suitable construction, carries a table, A' . The front part, A^2 , of the frame is recessed, boxed, or slotted, so as to form ways or guides in which to operate, by a longitudinal motion, one or more reciprocating locking-bars, which in the drawings are lettered and numbered from e' to e^{28} ; but in the construction of machines of this class the number of such bars may be varied as the work to be done may require. On each locking-bar I arrange one or more interlocking-dogs, $a a'$, &c., each preferably of rectangular shape, though other form may be employed with reference to securing the functions hereinafter set forth.

In a plane sufficiently near to the plane of the bars $e' e^3$, &c., to secure the results hereinafter described, I arrange one, two, or more vertical interlocking-bars, $b b'$, &c., and on each vertical bar I secure one or more grooved shifting blocks or travelers, $c c'$, &c., each such block having a groove, i , Fig. 7, extending diagonally across the face at an angle of about forty-five degrees to the direction of motion of the horizontal and vertical bars; or if such bars make other than a right angle with each other, then such groove i should exactly or approximately bisect such angle. Also, on such vertical bars I arrange dogs $s s'$, &c., similar to those on the horizontal bars and lettered a . The number of vertical bars b should equal in number and correspond in position with the operating-levers $B B'$, &c., of which I have shown five, though the number may be varied as the work to be done may require. Each lever plays through a slot in the table A' in the usual way, and alongside of a quadrant, q , which is notched, as at q' , at the ends of the fore and back movements of the lever, also as is usual. The lower end of each lever B is pivoted to a bracket, D , which is bolted or otherwise secured to the under side of the table, and a short arm, B^6 , extends out from the lower end of each lever, and is jointed by a pivot-pin to the upper end of the corresponding vertical bar b .

Alongside of each bracket D is a sliding plate, D' , which is connected, by a wrist and

slot, d' , with the lever, so as to receive a sliding motion therefrom in the direction of its length. In the other end of the sliding plate D' is a slot, d , which is made straight or horizontal at each end, but inclined somewhat at its middle part, substantially as shown in Fig. 1, the vertical height of the inclination being equal or about equal to the length of throw or motion which it is desired should be given to the valve or valves which control the fluid supply and discharge. Such valve or valves are arranged in the valve case or cases V V', and where a double arrangement of valves is employed they may be arranged to move simultaneously in opposite directions by connecting their stems v with the opposite arms v' of a rock-shaft, v^2 , supported on a post, V^2 . To give both valves a simultaneous motion, connection is made, by a rod, V^3 , from one arm of the rock-shaft v^2 to the slot d of the sliding plate D', a wrist, v^3 , on the rod entering and playing in the slot. The rod passes through a hole in a flange, d^2 , Fig. 6, made on the bracket D, and such flange also supports the shifting-plate D'. It will thus be seen that by sliding a lever, B, forward or back the corresponding sliding plate D' will also be moved in the direction of its length, and the inclined part of the slot d , acting on the wrist v^3 , will raise and lower the corresponding rod V^3 and thereby shift the valves.

As the present machine is chiefly designed for use as a part of a hydraulic apparatus, I have shown in the drawings portions of two pipes, P P', of which the one, P, leads from or is connected with any suitable accumulator or head or other source of hydraulic supply under pressure, and the other, P', leads to any convenient discharge or exhaust. At W, I have shown valve-cases for valves by which to shut off the fluid entirely when necessary, for purposes of repair or for other reasons. For each lever B, vertical bar b, valve-rod V^3 , and their connections, and in direct combination therewith, I arrange either a single valve-case, V^4 , as at the right of Fig. 6, or a double valve-case, V V', as elsewhere represented, and connect the same by suitable branch pipes, as represented, with the supply and discharge pipes P P'. With the single valve-case, V^4 , a single pipe branch or elbow, n , makes provision for a pipe-connection, thence to the cylinder or pressure-applying device by which the switch, signal, or gate is directly operated. In this case the valve is so constructed that a single motion in one direction lets on the pressure, cutting off the discharge, so as to shift the switch or raise the signal or gate, and a reverse motion cuts off the supply and opens the discharge, so as to let the signal or gate come down or permit the switch to be thrown back by a spring or other means; but with the double valve arrangement each lever B is intended to shift a valvular arrangement in V and V', so as to admit fluid-pressure through one branch, n' , to actuate one switch, signal, or

gate, while at the same time a fluid-pressure previously applied by the opposite motion of the same lever to actuate some other switch, signal, or gate is permitted to escape through another branch pipe, n^2 , the valves being properly constructed and arranged with reference to such ends; or, in order to give a throw in opposite directions to the same switch, signal, or gate, the two pipe-connections $n' n^2$ may lead to the opposite ends of a double-acting cylinder and be used alternately as supply and discharge pipes, so as in one adjustment of the lever and valves to effect a motion of the signal, switch, or gate in one direction, and by a reverse adjustment or throw to reverse the motion and position of such signal, switch, or gate. Valves and ports suitable for such work are described in Patent No. 229,341, granted to Guerber and myself June 29, 1880, though valves and ports of other suitable construction and adapted to the ends in view may be employed.

Returning, now, to the locking-bars and the interlocking dogs thereon, I do not deem it necessary to describe in detail the numerous combinations which may be made with the apparatus shown, but will merely indicate the manner of effecting interlocking combinations, which being understood, the constructor or builder skilled in this branch of the arts will have no difficulty in making such combinations of interlocking parts as the work to be done may require.

Taking first the horizontal locking-bars e^{15} and e^{17} , the dogs thereon, as on all the other bars, may be either fixed or adjustable. Preferably they are made fixed, and one convenient construction for such purpose is shown in Fig. 8 in enlarged view, where the dog a is shown as made with a rectangular hole through it. The bar e^{15} is passed through the hole, and the two are secured by a rivet. The similar dogs s, on the vertical bars b b', are arranged in such manner that they may, when properly adjusted, be thrown into and out of engagement with the dogs on the horizontal bars, the relative positions of such dogs when engaged being represented in Fig. 8, where the dog s on the vertical bar b' is shown as having sufficient thickness outside of b' to lap under the dog a of the horizontal bar. Also, for better illustration, I have shown in Fig. 7, by enlarged view, one of the grooved travelers or blocks, c. A wrist, x, from the corresponding bar e enters and plays in the groove i in such manner that as the block c is raised or lowered by the movement of its bar b it will shift the wrist x, and with it the horizontal bar e, to the right or left, as the case may be.

From Fig. 6 it will be seen that the dog a on the horizontal bar e^{15} and the dog s on the vertical bar b' are edgewise in engagement, so that the vertical bar b' is locked in position. In order, now, to unlock the vertical bar b' the operator gives, in the manner presently to be described, a back stroke or motion to the le-

ver B^3 . This, of course, raises the vertical bar b^3 , and the block c thereon causes the wrist x , which is connected to the bar e^{15} and plays in the groove i , to be shifted with the bar e^{15} to the right sufficiently far to cause the dog a to clear the dog s . The operator then gives to the lever B' a backward throw, and thereby raises the vertical bar b' sufficiently far to bring the dog s , which is thereon, up to the back side or face of the dog a , so as to prevent the possibility of giving to the horizontal bar e^{15} a back motion; and as the lever B^3 must, if it moves at all, move also the bar e^{15} , and as the latter is thus locked, it follows that the lever B^3 is also locked.

It will also be seen, from an inspection of Fig. 6, that the horizontal bars e^5 and e^7 carry each a dog, a' a^2 , which engage each other by a vertical lapping instead of a horizontallapping, as before, and that so long as a' retains the position shown, a^2 and its bar e^7 cannot be shifted to the right, and as e^7 is connected, through block c^2 and dog a^3 , with the vertical bar b^2 , it follows that the lever B^2 is locked; but the raising of the vertical bar b' , as above described, acting through the block c' thereon, shifts the horizontal bar e^5 to the right, so as to move the dog a' away from the dog a^2 on the bar e^7 , as a result of which the bar e^7 is unlocked, and with it the lever B^2 , which is connected with e^7 through the grooved block c^2 and dog a^3 . The lever B^2 may now be thrown back, so as, in the manner already set forth, to shift the horizontal bar e^7 to the right, and thereby bring the dog a^2 thereon up against the previously-moved dog a' , and thereby lock the lever B' . Also, the same motion brings another dog, a^3 , edgewise above a dog, s' , which is on the vertical bar b^4 , as a result of which the lever B^4 is locked. The lever B in the system here specially represented is connected with a valvular arrangement which, when the lever is thrown back, lets off the pressure and brings all or any desired number of signals to danger. In order, then, to lock all other conflicting connections—which in this instance we may suppose to be made with levers B' B^4 —I connect the corresponding vertical bar b , by the grooved block c^3 , with a horizontal bar, e' , and arrange on such bar e' the desired number of dogs a^4 a^7 in such position that when, by the raising of the vertical bar b , the horizontal bar e' is shifted to the right, such dogs a^4 a^7 will be brought into engagement with the dogs s^2 s^5 , which are secured to the vertical bars b^4 , as a result of which the levers B' B^4 will be locked in a forward position.

Each of the blocks c , c' , &c., may be grooved on the back faces as on the front, and like wrists connected with the back horizontal bars, e^2 , e^4 , &c., may work in such grooves, so that the same operations in locking and unlocking may be performed through the back horizontal bars as through the front ones; or, in lieu thereof, additional blocks grooved on their back faces may be provided for such purpose. If

the blocks c , c' , &c., are grooved on their back faces, such grooves may be inclined in the same direction as the front grooves, i , in which case the back horizontal bars connected therewith will move in the same directions as the front bars; or the back grooves may run in a reverse direction or crosswise of the front grooves, as illustrated by the dotted lines in the block c^2 , Figs. 6 and 9, in which case the back horizontal bars actuated thereby will move in a direction the reverse of the front bars with each stroke of the lever. With this explanation the skilled mechanic will understand how to vary or change the number, form, and relative arrangements of blocks c and dogs a and s with reference to each other, and to horizontal and vertical bars, so as to make any desired combinations in locking and unlocking, as the work to be done may require.

It will be understood that unlocking is to be effected by reversing the order employed in locking, though for most purposes locking and unlocking go on simultaneously, as is usual in the art.

I will next describe the manner in which I effect what is termed "preliminary interlocking."

Each lever B , at the beginning and end of its stroke, is held in place by the usual catch-rod R , which plays through a guide, R' , on the side of the lever in such manner that its lower end may be forced into the proper notch q' by means of a spring, r , Figs. 3 and 4, which operates to force the catch-rod down. On the upper end of each lever I affix a hollow shell handle, B^7 , in such manner as, by a screw-bolt, y , that the shell handle may have a slight range of rotative motion on its own axis, say, about a one-eighth turn, more or less. On the inside of the shell handle, and opposite to the catch-rod R , I make a spiral groove, by means of two spiral ribs, r' , and on the catch-rod R , I make a teat, wrist, or spline, r^2 , and of such size and form and in such position that it may enter and move readily in the groove formed by the ribs r' . It will then be seen that the operator, by taking hold of the handle B^7 and giving it a one-eighth turn, can screw up the catch-rod almost instantly, so as to withdraw its lower end from the notch q' , and that then the lever is free to be moved. On completing the lever stroke or motion he may rotate the handle back, though ordinarily this will not be necessary, since the screw having a steep pitch, the spring r may be made sufficiently powerful for that purpose. As soon as the lever B commences, say, its back stroke, it begins to raise the corresponding vertical locking-bar b , and thereby in the manner described shift the corresponding horizontal bar, and in doing so bring the dogs a on such bar so far past or lapping onto the dogs of some other bar that the desired locking is practically effected—that is to say, the locking is effected in a practical sense as soon as the edges of the dogs or block begin to lap one onto another edgewise; but this,

which I term "preliminary interlocking," is effected in part, at least, before the valve-rod V³ begins its stroke, since during the first part of the motion of the lever a straight or horizontal part of the slot d is sliding along on the wrist v³; but as soon as this preliminary interlocking is effected the wrist v³ begins to be engaged by the inclined part of the slot d, and then, but not till then, motion is imparted to the valves in the valve-case below, such as to cause the fluid-pressure to become operative in shifting a switch-signal or gate, or permitting the same to be done. By the time the inclined part of the slot d has traversed the wrist v³, so that the latter shall be at the upper end of the incline, the valves will have received their entire or complete motion or throw, and allowing time for the fluid-pressure to act, the shifting of switch, signal, or gate will be complete.

The rest of the motion of the lever B, whereby the upper horizontal or straight part of the slot d is caused to traverse the wrist v³, produces no effect on switch, signal, or gate, but simply completes the unlocking of such connections as ought to be unlocked preliminary to some other adjustment or combination; or, in other words, it takes certain of the dogs on one bar entirely out of an edgewise engagement with such dogs on another bar as at the beginning of the lever-stroke were interlocked therewith. Hence my improved apparatus secures not only preliminary locking, which is practically an important feature of apparatus of this class, but it also secures what may be termed "subsequent unlocking," by which I mean the unlocking of such combinations or devices as ought to be unlocked after, and only after, those devices have been shifted, the shifting of which ought to precede the shifting of the other devices so unlocked—meaning by "devices" as last used a switch, signal, or gate; and this "subsequent unlocking," as I use the term herein, is effected by and during the latter part of the stroke or motion of the lever, which, in its previous stroke or motion, has effected the desired shifting or setting of switch or signal. On the forward or reverse stroke of the lever B the operation is in all respects exactly reversed, the subsequent unlocking of the previous or back stroke now being or constituting preliminary interlocking, and the previous preliminary interlocking being now subsequent unlocking, and the valves being reversed as the wrist v³ slides down the moving incline of the slot d, so that the shifting of switches, signals, or gate is effected at an intermediate point of the operation, as before.

In the use of the terms "horizontal" and "vertical" as applied to the moving parts designated, I do not mean to use them in an absolute, but only in a relative, sense, and as related to each other, or in the sense of crossing bars exactly or approximately horizontal and vertical to each other; and under the terms "dogs" and "blocks" I include any known

devices suitable for the purpose of engaging one with another, and disengaging one from another, on the proper movement or shifting of the bar or bars which carry and actuate them; also, where I have indicated dogs, bars, &c., as a class by a single letter, as a e, &c., I include the same letters as numbered 1 2, &c.

In Fig. 2 I have shown a modified form of apparatus for giving to the valve-rod V³ the motions described. In this figure the slide D' has the inclined part of the slot d of Fig. 1, and the last motion for which provision is made in Fig. 1 by the straight or horizontal end parts of the slot is here provided for by the use of a sector, m, to which the slide D' is pivoted, and which itself is to be pivoted to the bracket D in such position that the wrist-pin d' will operate on or over the sector as follows:

The sector has three faces, z z' z², slightly curved, the middle one being a little lower than the other two. The wrist-pin d' at the beginning of the lever-stroke slides along or clear of the surfaces z z', so as not to move the sector m nor the plate D' until it comes to the shoulder at the end of z². It engages that shoulder and shifts the sector far enough to cause the slot d to traverse the wrist therein until the wrist reaches the upper end of the incline, with the functional result already stated. The sector m has by that time been so far tilted over that the pin d' clears or rides over the face z² during the rest of the stroke of the lever. With a reverse stroke of the lever the reverse effect takes place. The pin d' rides or clears the surfaces z² and z' without moving the sector, engages the shoulder at the end of z, and tilts the sector back, so as to cause the slot d to traverse the wrist until the wrist comes to the lower end of the incline, and then the pin d' rides over the face of z without moving the sector until the lever completes its back stroke; but in respect to these connections between the lever and valve-rod I do not limit myself, since other suitable connection may be employed, such as will make provision for the moving of the valves at a point intermediately between the beginning and the ending of the locking or unlocking of the interlocking devices; also, in so far as relates to the use of the hydraulic apparatus described, other forms of interlocking apparatus may be employed.

While I have described this as a hydraulic apparatus, many features of the invention, and especially the shifting, the interlocking, and unlocking parts, may be applied in a pneumatic apparatus, wherein a reservoir of compressed air shall take the place of the hydraulic head, and suitable air cocks or valves shall be substituted for the valves referred to, and the valve-rod V³, or its mechanical equivalent, be arranged to actuate, substantially in the manner described, such air cocks or valves; and hence, for the purposes of the present case I designate such hydraulic apparatus or such substitute air apparatus generally as "fluid-

pressure" apparatus, the construction of apparatuses suitable for the uses thus designated being well known in the art.

I claim herein as my invention—

- 5 1. As a means for operating a catch-rod, a rotative handle, B^7 , arranged on the lever to which the catch-rod is applied, and connected by a spiral teat or rib and groove with the catch-rod, substantially as set forth.
- 10 2. In a fluid-pressure interlocking-switch and signal apparatus having interlocking bars which cross each other, the combination of a lever and valve-rod with suitably-interposed connections of such lever and valve-rod, where-
15 by the initial movement of the lever shall shift a locking-bar for preliminary locking in advance of the movement of the valve which turns on the fluid-pressure, substantially as set forth.
- 20 3. The combination of valve-actuating mech-
ism, unlocking-gear, and a lever for operating both, whereby the valve or valves shall receive a full stroke in advance of the complete un-
locking action of the interlocking mechanism,
25 substantially as set forth.

4. In a fluid-pressure apparatus for shifting or moving a signal, switch, or gate, the combination of an interlocking mechanism operative by a lever motion to effect interlocking in advance of the application of the fluid-pressure, a valve-connection which shall receive its proper throw from a continuation of the same lever motion before the completion of the movement of the interlocking devices, and an un-
locking mechanism operative by a still further movement of the same lever in unlocking after the fluid-pressure connection has received its proper throw, substantially as set forth.

5. Side bearing dogs $a' a^2$, arranged on bars $e^5 e^7$, in combination with vertical and operat-
ing bars b' , substantially as set forth.

In testimony whereof I have hereunto set my hand.

HARVEY TILDEN.
